MACHINE USED IN CONSTRUCTION TWINE
HEDDLE

Isaac Andrews and Howard O. Coddington, Spartanburg, S. C., assignors to Andrews Company, Spartanburg, S. C.

Application September 27, 1935, Serial No. 42,502

7 Claims. (Cl. 28—3)

This invention relates to a machine for constructing loom harness and more particularly to a mechanism to be installed on the usual twine heddle forming machine for positioning metal clips at the ends of the heddle bar receiving eyes of the heddles, so that the usual continuous twine harness may be cut providing independent twine heddles for use with the usual metal bars employed in supporting the usual steel heddles now commonly used in weaving a fine grade of cloth.

The primary object of the invention is to provide a twine heddle harness made up of a plurality of independent twine heddles so that the number of heddles per inch may be changed to meet various requirements in weaving the various grades of cloth, and eliminating the necessity of removing the entire loom harness when a change in the texture of the cloth to be woven is to be made.

An important object of the invention is to provide means for engaging the twine of the harness after it has passed through the loom harness machine, the twine engaging means holding the twine separated in such a way that the clips will be accurately positioned without danger of clipping together more than the required number of twines.

Another object of the invention is to provide means for stretching the heddles taut while the clips are being applied to the twine, in the formation of the supporting eyes of the heddles, thereby insuring heddles being formed of uniform length.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 20 is a longitudinal sectional view through one of the yieldable presser rods.

Figure 21 is a perspective view illustrating the worms and chains of gearing employed in operating the worms.

Figure 22 is a sectional view through the frame and worms.

Figure 23 is an elevational view illustrating the means for feeding the metal ribbon of which the clips are formed.

Referring to the drawings in detail, the usual twine heddle harness forming machine, is indicated generally by the reference character 5, and as shown includes the usual eye forming fingers 6 and 7, the twine of which the harness is formed, being indicated by the reference character A.

As previously stated, the present invention resides in the provision of means on the usual twine heddle forming machine, for separating the twine of the heddles and clipping the ends thereof together, in the formation of the eyes of the heddles.

The means for accomplishing this result, includes parallel worms or spirals 8, operating in opposite directions, and mounted on the frame of the machine at a point where the twine heddle harness under construction must pass directly thereover and in contact with the worms.

These worms or spirals 8 are formed at the forward ends of the shafts 9 that have gears 10.

mounted on their rear ends that receive motion through the train of gears embodying the gears 11, 12, 13 and 14, which in turn are operated by the main or power shaft 15.

- 5 Secured to the forward ends of the shafts 9, are fingers 17 that have their inner surfaces beveled in such a way that as the fingers rotate, they will move between adjacent heddles of the twine harness formed, separating the heddles and 10 moving the heddles into the grooves of the worms or spirals 8, where the heddles are fed rearwardly to the clip formers.

In order that the twine heddles will be held within the grooves of the worms, while they are 15 being fed through the machine, elongated inverted U shaped guards 18 are provided, the guards being disposed directly above the worms in a manner to close the upper portions of the grooves of the worms or spirals.

- 20 The usual twine heddle harness is constructed in a continuous strip, the ends of the heddles of the harness being formed by twisting the twine over the twine B which forms the ends of the individual heddles. The twine B extends through 25 the clamps 19 pivotally mounted on opposite sides of the frame of the machine at 20, for purposes to be hereinafter more fully described.

Mounted on the frame of the machine and disposed at opposite sides of the upper portion of 30 the frame, are the clip formers which form and position the clips in the construction of the eyes at the ends of the twine heddles, and in view of the fact that both of these formers are identical in construction, only one of the formers will be 35 described in detail.

- 35 The metal strip or ribbon of which the clips are formed, is fed longitudinally of the machine and passes through longitudinal slots formed in the guide blocks 21 that have their inner ends spaced apart and formed with shoulders 22. 40 Spaced from the guide blocks and disposed directly under the adjacent ends thereof, is an anvil indicated by the reference character 23 and on which the clip is formed and pressed around the twine heddle near the ends of the heddle under construction, forming the eyes.

The former frame which supports the former mechanism, is indicated by the reference character 24, and rises from the frame of the machine, the former frame having bearings 25 in which the shaft 26 operates, which shaft is provided with the sprocket 27 over which the power chain operates, the power chain being indicated by the reference character 28. This power chain transmits rotary movement to the shaft 26 which in turn operates the clip forming mechanism.

On the forward end of the shaft 26 is a disk 29 formed with a guide slot 30, in which the pivot pin 31 operates, the pivot pin having a head constructed to fit within the guide slot in such a way that the head may move freely throughout the length of the slot.

The pin 31 is secured to the upper end of the link 32 to which the pin 33 is connected, the pin 65 33 being secured to the slide 34 that moves in the guideway 35 formed in the front surface of the former frame.

The former carried by the slide includes an inner member 36 and an outer member 37, the 70 inner member 36 having bores in which the pins 38 operate. Springs 39 are disposed in the bores and bear against the pins, normally urging the pins downwardly.

Stop screws 40 extend into the former and are 75 adapted to engage the shoulders 41 of the pins

38 restricting downward movement of the pins 38.

One of these pins 38 carries the blade 42 while the other pin 38 carries the presser foot 43 which is of a length greater than the length of the blade 42, so that the presser foot 43 operates in advance of the blade 42 with the result that the metallic strip or ribbon of which the clips are formed, is securely held against movement while the metal strip or ribbon is being cut by the blade 42.

10 The inner member 36 is provided with an extension 44 disposed between the blade 42 and presser foot 43 and engages the clip being formed, bending the clip around the twine of the heddle, forming the heddle eye. The outer member 37 15 is formed with a bore in which the pawl 45 is mounted, the pawl 45 having a notch formed in the inner end thereof adapted to engage the upper edge of the blade 42, as shown by Figure 7 of the drawings, restricting movement of the 20 blade 42 in one direction and with respect to the member 37.

One end of the pawl 45 supports the head 46 which is formed with a beveled inner end engaged by the cam 47 forming a part of the bar 25 48 which is slidably mounted on the outer member 37, the upper end of the bar 48 being supplied with a pin 49 adapted to engage the pin 50 extending from the bar 51 when the slide 34 moves downwardly in forming the clip.

30 Thus it will be seen that due to this construction, the blade 42 is held in its extended position until the blade has cut a length of the metal strip or ribbon, to form a clip, whereupon further downward movement of the slide will cause the 35 pawl 45 to be retracted, allowing the blade 42 to move upwardly within the outer member, permitting the foot and extension to move to positions to form the clip.

35 The metal strip or ribbon from which the clip is formed moves over the sliding plate 52 which carries dogs 53 that engage the metal strip pressing the strip against the sliding plate so that the strip will be moved along with the plate, or in the direction of the arrow as shown in Figure 23 40 45 of the drawings, with each movement of the plate 52. Lever 54 has connection with the sliding plate 52 and moves the plate 52 in one direction. This lever 54 is operated by the cam 55 mounted on the shaft 57 there being provided a coiled spring 58 50 for moving the plate 52 to feed the metal strip or ribbon.

60 Disposed under the former is a guide plate 59' on which the plate 59 operates, the plate 59 providing a support for the fingers 60 and 61, the 55 latter fingers being pivotally mounted on the plate 59 to move laterally to positions as shown by Figure 6 of the drawings, spreading the heddles adjacent to the heddle being supplied with clips, laterally so that the twines of the adjacent heddles 60 will not interfere with the operation of the former.

65 As clearly shown by Figure 6, the fingers 61 are formed with cut out portions presenting inclined surfaces to be engaged by the stationary rod 62 when the plate 59 is moved upwardly by the cam 63 mounted on the shaft 56. Coiled spring 64 which connects the plates, is of the contractile type and acts to urge the plate 59 downwardly.

70 Operating above the fingers 60 and 61, are pivoted fingers 65 that also have cut-out portions presenting inclined surfaces 66 engaging the spring pressed pin 67 so that when the fingers are moved rearwardly with their support, the fingers 75

will be moved laterally separating the heddles of the harness being formed.

Shaft 56 also supports cams 65' and 66', and as shown, the cam 65 is arranged to operate in advance of the cam 66'. The cams 65' and 66' engage the lower ends of the vertically operating cam plates 67' and 68 respectively, which operate in the guide member 69 secured under the body of the machine. The cams 70 and 71 operate through an opening formed in the base of the machine and contact with the upstanding ends 72 of the plates 73 which slide in the guide-ways 74 formed in the body of the machine.

Contacting with the ends 72 of the plates 73, are pins 75 that have their outer ends engaging the adjusting screws 76 carried by the arms 77 pivotally mounted on the frame of the machine at 78, the arms having their forward ends connected to the forming arms 79 and 80 in such a way that as the arms 77 are operated, the members 79 and 80 slide within their guide-ways to accomplish the purpose of the invention.

The strokes of the forming arms 79 and 80, are regulated by the screws 81 that extend through the arms 77 and engage the post 82 forming a part of the bracket that supports the arms 77. Secured to the adjacent ends of the arms 77 is a coiled spring 83 which normally draws the ends of the arms with which the spring is connected, towards each other, resetting the forming arms and moving the mechanism to a position for another operation.

Cam grooves 84 are formed in the upper surfaces of the forming arms 79 and 80, which cam grooves accommodate the cams 85 so that when the forming arms 79 and 80 move under the cams 85, the forming arms 79 and 80 will be moved downwardly against the action of the springs 86 supported directly under the arms 79 and 80, in a manner to press the clip into shape.

Assuming that the forming arms 79 and 80 are in a position as shown by Figure 10 of the drawings, and the blade 42 has cut a length of the strip. As the extension 44 presses the length of metal cut, downwardly onto the anvil, the length of metal is bent into U formation. The extension 44 now moves upwardly, and the forming arm 79 now moves inwardly pressing one side of the U shaped clip downwardly into engagement with the twine heddle as shown by Figure 12.

With further movement of the machine, the cam 66 comes into play and moves the forming arm 80 towards the forming arm 79 with the result that the opposite side of the length of metal cut, is bent inwardly as shown by Figure 13.

As the forming arm 80 contacts with the forming arm 79, the forming arm 80 moves to a position to complete the clamping operation or the operation wherein the clip is pressed into close engagement with the twine heddle. It will of course be seen that when the forming arm 80 completes the clip, the forming arm 79 has been returned to its normal inactive position.

After the loom harness has been completed and passed through the machine, the portions of the heddles beyond the supporting eyes thereof are cut in any suitable manner, providing a plurality of twine heddles which may be arranged on the usual heddle supporting bars of a loom to provide a harness of any desired number of heddles, and providing a harness wherein the number of heddles may be increased or decreased, at the will of the operator.

What we claim is:

1. An apparatus for forming twine loom harness into individual twine heddles, including an anvil, means for feeding a metal strip to the anvil, worms adapted to feed the loom harness to the anvil, means for cutting a length of metal 5 from the metal strip, and means for bending the length of metal cut from the strip, around the heddles at the ends of the heddles, forming eyes at the ends of the heddles, whereby the harness may be cut into individual twine heddles. 10

2. An apparatus for forming twine loom harness into individual twine heddles, including an anvil, means for feeding a strip of metal to the anvil, means operating above the anvil for holding and cutting a length of metal from the metal strip and forming the length of metal cut into a substantially U shaped clip, means for feeding the twine loom harness through the machine and successively stopping the heddles over the anvil, and means for bending the clips around the ends 20 of the heddles forming eyes, whereby the harness may be cut providing individual twine heddles.

3. An apparatus for applying metal clips to the heddles of twine loom harness, including an anvil, worms forming a part of the apparatus, 25 said harness adapted to run in the grooves of the worms, feeding the harness to the anvil, means for holding the harness in the grooves against displacement, and means cooperating with the anvil for bending the clips around the heddles form- 30 ing eyes at the ends of the heddles.

4. A device for applying metal clips to the heddles of a twine loom harness, forming eyes at the ends of the heddles, said device including an anvil, means for feeding the heddles to the 35 anvil, means for feeding a length of wire to the anvil to be cut into clip lengths, vertical movable bending members adapted to bend the clip into U formation, bending members moving towards each other and adapted to bend a clip 40 therebetween, and means for moving one of the bending members in advance of the other bending member whereby a clip is bent around the heddle, securing the strands of the heddle together and forming eyes at the ends thereof. 45

5. A device for applying metal clips to the heddles of a twine loom harness, forming eyes at the ends of the heddles, said device including bending members adapted to bend the clips around adjacent twines of the heddles, forming 50 eyes, worms adapted to feed the twines to the bending means, elongated inverted U-shaped guards disposed above the worms and contacting with the worms, and said guards adapted to hold the twines in contact with the worms as 55 the twines are fed to the bending members.

6. A device for applying metal clips to the heddles of a twine loom harness, forming eyes at the ends of the heddles, said device including clip bending members, worms adapted to feed the 60 twine of the heddles to the clip bending members, and fingers on the ends of the worms and adapted to engage the twine of the heddles, directing the twine to the worms.

7. A device for applying metal clips to the hed- 65 dles of a twine loom harness, forming eyes at the ends of the heddles, said device including clip bending members adapted to bend clips around adjacent twines of the harness providing eyes, stretching members adapted to engage the twine 70 of the heddles pressing the twine into engagement with the bending members, and means for feeding the clips to the heddles.

ISAAC ANDREWS.

HOWARD O. CODDINGTON. 75
